N. PETERS, Photo-Lithographer, Washington, D. C.

UNITED STATES PATENT OFFICE.

BARNARD FIELD STEVENS, OF SCOTIA, NEBRASKA.

TRACE-CARRIER.

SPECIFICATION forming part of Letters Patent No. 326,802, dated September 22, 1885.

Application filed July 11, 1885. (No model.)

To all whom it may concern:

Be it known that I, BARNARD F. STEVENS, a citizen of the United States, and a resident of Scotia, in the county of Greely and State of Nebraska, have invented certain new and useful Improvements in Trace-Carriers; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of a portion 15 of a set of harness provided with my improved trace-carrier. Fig. 2 is a similar view, on an enlarged scale, of the carrier detached; and Fig. 3 is a detail view of a slight modification in the snap-hook.

20 Similar letters of reference indicate corresponding parts in all the figures.

My invention has relation to trace carriers; and it consists in the improved construction and combination of parts of a trace carrier, 25 which at the same time fills the function of a buckle for uniting the back, crupper, hip, and spreader straps, as hereinafter more fully described and claimed.

In the accompanying drawings, the letter A 30 indicates the main frame of the carrier, which frame may be either rectangular or oblong, as shown in the drawings, and the forward portion of this frame forms a bail, B, for the attachment of the back-strap C, while the 35 rear end of the frame forms a bail, D, for the attachment of the crupper-strap E. At the sides of the frame are bails or loops F F, for the attachment of the hip-straps G and spreader-straps H, thus making the frame the 40 point of union for all the parts of the harness which are supported upon the rump of the horse. The snap-hooks J are composed of the hook portions I and the snaps M. The parts I can be bent upward at their middle, as 45 shown, and secured to the frame A by being bent partly around it, so as to clamp it securely, and the parts K are then formed by being bent upward and outward, as shown at L, so as to form an easy and con-

venient point of attachment for the cockeyes 50 of the trace. The spring-tongues M M of the snap-hooks are secured to the upper bent portions of the hooks, and their free ends bear against the inner sides of the upwardly-curved outer ends of the hooks, and are curved 55 slightly downward, as shown at N, so as to allow the cockeyes to pass freely between them and the upturned ends of the hooks; or they may be bifurcated, as shown at Q, Fig. 3. A wide bail, O, is secured at its ends, slightly 60 forward of the hooks, to the sides of the frame, and projects slightly above the upper sides of the hooks, serving as a guard-bail to prevent the reins from becoming caught in the hooks, and two converging and upwardly and forwardly curved guard-strips, P P, are secured 65 to the rear portion of the frame, projecting over the middles of the snap-hooks, serving as guards for the tail of the horse, preventing it from being caught in the hooks. In this 70 manner it will be seen that I have constructed a trace-carrier which unites all the pieces of the harness meeting above the hip of the horse, which has hooks into which and from which the cockeyes of the traces may be easily inserted or removed, and which has guards 75 which prevent the reins, the tail of the horse, or any other object from becoming caught in the hooks.

Having thus described my invention, I claim 80 and desire to secure by Letters Patent of the United States—

1. A trace-carrier having snap-hooks secured near its middle portion, said hooks consisting of the portion I, curved upward at its 85 middle, and having the upward bent ends K, and the intermediate portion bent so as to 90 clasp the frame A, and the snap M, the ends of which are slightly curved and secured intermediately to the bent portion of the part I, substantially as and for the purpose set forth.

2. The combination of the carrier-frame having the bail at its rear end for the crupper-strap, the bail at its forward end for the back-strap, and the bails or loops at its sides for the hip-straps and spreader-straps, the snap-hooks secured with their inner ends together,

and having their outer portions secured to the sides of the carrier-frame, a wide guard-bail secured with its ends to the sides of the carrier-frame forward of the snap-hooks, and 5 projecting slightly above the upper sides of the same, and the converging and united forwardly and upwardly curved guard-strips secured to the rear end of the carrier-frame, as and for the purpose shown and set forth.

In testimony that I claim the foregoing as to my own I have hereunto affixed my signature in presence of two witnesses.

BARNARD FIELD STEVENS.
